LOOSE-LEAF BINDER

Harold E. Baughman, Glendale, Calif., assignor
to Aero Publishers, Inc., Glendale, Calif.

Application April 20, 1942, Serial No. 439,698

7 Claims. (Cl. 129—1)

This invention relates to an improved loose-leaf binder for note-books and the like, and has particular reference to semi-permanent books intended to be kept up to date by the replacement or addition of revised or supplemental subject matter.

The split ring type of loose-leaf note-book, as heretofore used, is usually provided with opening mechanism and an exposed metal shell therefor, some types having the mechanism riveted to the backbone of the cover proper. The circular split rings cause binding and tearing of the outside sheets of the filling material because of the wedging action as the covers are closed. It is accordingly an object of this invention to provide an improved loose-leaf binding arrangement for semi-permanent records, such as catalogs, service manuals, or the like, wherein replacement or supplemental material is to be added at intervals.

In a previous application, Serial No. 405,340, filed August 4, 1941, I disclosed a loose-leaf binding arrangement wherein a series of continuous rings were formed with marginal metal strips embedded in the backbone. The present invention permits complete elimination of metal parts and also utilizes individual circular or semi-circular rings which may be cut from hard "plastic" tubing of a wide variety of materials and colors.

It is accordingly an important object of this invention to provide an improved and simplified loose-leaf book backbone that eliminates the need of any metal, and in which the leaf retaining rings can be rigidly supported and simply assembled in the backbone.

It is a further object of this invention to provide an improved and simplified loose-leaf binder closely approximating the appearance and arrangement of a permanently bound book, the filling material having open stemmed T slots permitting its ready insertion and removal from continuous rings retained in fixed relationship to the back of the book, so that the book closely resembles a bound book which can be imprinted in the conventional manner.

It is also an object of this invention to provide an improved and simplified loose-leaf book construction wherein continuous semi-circular securing rings are individually supported in a folded and glued cardboard backbone by means of a supporting non-metallic strip cut out to receive a portion of the rings and having resilient tongues struck from the strip projecting through the rings to lock them into the apertures in the strip, the cardboard being folded and glued over

the non-metallic strip and the free ends of the tongue to provide a rigid backbone into which the rings are partially embedded; the assembly being further retained in position by the usual inner lining of the book covers and/or by a finishing fabric strip suitably slotted to be applied over the securing rings in contact with the backbone.

Other and further objects and advantages of my invention will become apparent as the description of the invention proceeds.

In the accompanying drawing—

Figure I is a perspective view of an opened loose-leaf book showing the construction of this invention, parts of the lining material and backbone being broken away to disclose details of the construction; and including a preferred typical sheet of paper for use therewith.

Figure II is a fragmentary perspective of the non-metallic strip which locates and supports the securing rings, one ring being shown in place in an aperture in the strip.

Figure III is a cross-section of this device of Figure I showing details of the continuous securing ring mounting.

Figure IV is a section through a modified form of this invention corresponding to Figure III, the modification embodying the use of semi-circular rings.

Figure V is a section through another modified form of this invention using a semi-circular ring wherein the base is deformed to more solidly seat in the aperture therefor.

As shown on the accompanying drawing, the invention relates to mounting continuous circular or semi-circular D shaped securing rings 10 relative to the covers and back of a book structure; the book covers comprising cardboard boards 11, in the case of stiff covers, and a back 12, an outside cover material 13 being applied thereto in the usual manner to provide hinge lines 14. The inside surfaces of the covers may be finished with lining paper 15, and an inside lining fabric 16 applied to the back if desired.

The securing rings 10 are conveniently transverse sections of extruded or cast plastic tubes which can be formed in a variety of cross-sections. Almost any thermo-setting synthetic resin plastic that can be suitably formed will be satisfactory for the purpose, so that the choice may be decided by cost and availability under existing conditions. An example is phenolic formaldehyde resin or urea formaldehyde resin.

The use of continuous rings makes it desirable to use marginal T slots in the filler material,

which I have found can be readily inserted or stripped from the rings without damage to the sides of the T slot in the paper. Preferably the paper filler should be peeled off the rings with a movement aligned with the axis thereof, rather than to pull the paper out from the free edge of the book.

The securing rings are seated in apertures 17 in a non-metallic strip 18, a central tongue 19 being cut into the strip to pass through the ring and press it into the apertures, the resiliency of the tongue being sufficient to permit it to be sprung upwardly to allow the ring to be slid into place under the free end of the tongue.

The supporting strip may be made of plastic, fibre board, or thin plywood, an example being a plain or colored cellulose nitrate plastic.

In each of the forms of the invention the supporting strip 18 is bound in a triple layer of cardboard forming a backbone which may be an inner backbone supplementing a cover backbone or may itself form the sole backbone of the book binding. The triple cardboard backbone comprises a central layer 20 underlying the supporting strip 18, edges 21 and 22 of the cardboard being cut out to fit over the rings, folded in overlapping relationship, and glued down on top the supporting strip 18.

It is convenient to provide a fabric finish and cover strip 16 which may have slotted margins to extend around the rings 10 or may be slotted as at 23 to slip over the rings to be glued in place. Such a cover strip acts as a trim to the central portion of the inside of the covers, and strengthens the hinge lines 14.

Figure III is a considerably enlarged cross-section wherein the several layers of the backbone have been shown somewhat idealistically for clearness. Actually the several cardboard layers are glued together and to the securing strip 18 to form a substantially solid lamination, so that the margins will be compressed into contact.

It will be evident that circular rings 10 can be used as in Figures I and III or a semi-circular or D ring 16a as in Figures IV or V, the latter having offset portions 24 in the stem or flat side which seat solidly into the apertures in the supporting strip 18.

It will thus be seen that I have invented an improved and simplified loose-leaf book wherein the back of the book has the appearance of a permanently bound book since no rivets are required to retain the securing rings in position, wherein the capacity of the book is increased without liability of wedging the outside sheets thereof between the covers and the rings, and wherein the entire construction avoids the use of metal while providing a substantial and rigid construction.

Having thus described my invention and the present preferred embodiments thereof, I desire to emphasize the fact that many modifications may be restored to in a manner limited only by a just interpretation of the following claims.

I claim:

1. In a loose-leaf book, the combination comprising a backbone carrying continuous securing rings partially embedded therein and book covers hinged to the backbone, the backbone being built

up as a glued assemblage of cardboard folded over a non-metallic ring securing strip having transverse apertures to support the rings and an integral tongue associated with each aperture and struck from the strip material, said tongue passing through the ring and serving to resiliently hold the same in said apertures.

2. In a loose-leaf book, the combination comprising a backbone carrying fixed securing rings partially embedded therein and book covers hinged to the backbone, the backbone being built up as an assemblage of cardboard folded over a ring securing strip having transverse apertures to support the rings and an integral tongue associated with each aperture and struck from the strip material, said tongue passing through the ring and serving to resiliently hold the same in said apertures.

3. In a loose-leaf book, securing rings, a ring supporting backbone comprising a ring securing strip having transverse apertures to receive and support the rings and longitudinal tongues integrally struck from the strip material and bridging said apertures, said tongues being adapted to be sprung upwardly for the insertion of the rings and to resiliently hold said rings seated in the apertures in the strip, and cardboard folded over said securing strip to complete the backbone structure.

4. In a loose-leaf book, securing rings, a ring supporting backbone comprising a ring securing strip having transverse apertures to receive and support the rings and longitudinal tongues integrally struck from the strip material and bridging said apertures, said tongues being adapted to be sprung upwardly for the insertion of the rings and to resiliently hold said rings seated in the apertures in the strip, and cardboard enveloping said securing strip in overlapping folds to secure said tongue and rings in position.

5. In a loose-leaf book, securing rings, a ring supporting backbone comprising a ring securing strip having transverse apertures to receive and support the rings and longitudinal tongues integrally struck from the strip material and bridging said apertures, said tongues being adapted to be sprung upwardly for the insertion of the rings and to resiliently hold said rings seated in the apertures in the strip.

6. In a loose-leaf book, a ring supporting backbone comprising a ring securing strip having transverse apertures to receive and support the rings and longitudinal tongues integrally struck from the strip material and bridging said apertures, said tongues being adapted to be sprung upwardly for the insertion of the rings and to resiliently hold said rings seated in the apertures in the strip, and pre-formed securing rings each having an offset base adapted to seat in a corresponding one of said transverse apertures.

7. In a loose-leaf book, having at least one securing ring, a tongue extending through said ring, and a cardboard backbone underlying said tongue and having marginal folds cut out to fold over the tongue in the region of the securing ring, the marginal folds overlapping each other and being glued in place to anchor the ring in position in the backbone.

HAROLD E. BAUGHMAN.
